Primary Examiner — Mark A Goodwin(74) *Attorney, Agent, or Firm* — Klintworth & Rozenblat IP LLP(57) **CLAIM**

The ornamental design for a planter row unit member, as shown and described.

DESCRIPTION

FIG. 1 is a perspective view showing a planter row unit member according to our new design in context of an example planter row unit;

FIG. 2 is a perspective view of the planter row unit member depicted in FIG. 1 shown in isolation;

FIG. 3 is a first side elevational view thereof;

FIG. 4 is a second side elevational view thereof;

FIG. 5 is a first end elevational view thereof;

FIG. 6 is a second end elevational view thereof;

FIG. 7 is a first plan view thereof; and,

FIG. 8 is a second plan view thereof.

The broken line representations in the figures depict unclaimed environment and form no part of the claimed design.

1 Claim, 5 Drawing Sheets(56)
